UNITED STATES PATENT OFFICE.

MOISEY M. SEREBRIANOI, OF SALTYKOVKA, UNION OF SOCIALIST SOVIET REPUBLICS,
RUSSIA.

PLASTIC COMPOSITION.

No Drawing. Application filed September 26, 1928, Serial No. 308,574, and in the Union of Soviet
Republics February 3, 1926.

My invention relates to plastic compositions and has a particular reference to compositions made from waste fibrous materials, such as scrap leather, and to the process of manufacturing these compositions.

The object of my invention is to provide a composition suitable for manufacturing imitation leather, board, linoleum, paper, etc.

For this purpose I am using waste material from leather manufacturing plants, such as scrap leather, leather dust etc. These materials are sorted out to separate foreign articles and are placed in a tank with water. This tank is then heated until leather becomes soft and expanded. If necessary the water may be brought to the boiling temperature. About 5% of sodium chloride (NaCl) can be added to the water in order to remove the fat from leather. This salt also tends to render the finished product more supple.

In order to increase the plasticity of the product turpentine can be also added. By adding paints or dyes into the mixture the finished product may be obtained of any desired color.

The mixture, when leather becomes thoroughly soaked and softened, is compressed into sheets and plates in cold or, preferably, hot presses. The resultant material is very strong and resilient and can be used as a substitute for leather.

Cork can be added to the mixture in which case the product will have properties of an ordinary linoleum.

For manufacturing paper the composition is compressed into logs or blocks of a size

suitable for feeding into ordinary grinding and chipping machines in paper mills. The paper pulp made from these blocks is suitable for manufacturing paper and paper board of ordinary commercial grades and using ordinary paper mill machinery. Other fibrous materials can be added to the composition in any suitable quantities.

Important advantages of my composition are that it utilizes cheap scrap and waste materials and the resultant product possesses good commercial merits.

I claim as my invention:

1. In a process of making plastic composition, consisting in soaking and heating in water leather scrap, adding turpentine, and compressing same into sheets.

2. In a process of making plastic composition, consisting in soaking and heating in water leather scrap, adding sodium chloride and turpentine and compressing the resultant mixture into sheets.

3. In a process of making paper, consisting in soaking and heating in water leather scrap, adding turpentine, compressing same into blocks, and making pulp and paper from said blocks by ordinary processes used in the manufacture of paper.

4. A plastic composition, made of leather scrap, soaked and heated in water with turpentine and compressed into sheets.

5. A plastic composition, made of leather scrap, soaked and heated in water with sodium chloride and turpentine, and compressed into sheets.

In testimony whereof I affix my signature.

MOISEY M. SEREBRIANOI.
